UNITED STATES PATENT OFFICE

JOSEPH L. HECHT, OF DAVENPORT, IOWA

CLOSURE FOR RECEPTACLES

Application filed May 7, 1929. Serial No. 361,033.

This invention relates to closures for receptacles, and has reference more particularly to closures for bottles, flasks, and the like, in which a cap or holder carrying on its interior 5 a sealing member of resilient material, is engaged with the neck of the bottle by a turning or screwing motion, and thereby forces the sealing member tightly against the end or mouth of the neck.

10 In closures of this type, it is usual to cement or otherwise fasten the resilient sealing member fixedly to the holder or cap, with the result that in turning the holder to seat the sealing member against the end of the bottle 15 neck, said member will grind against said end, and by these repeated turning actions, the sealing member will become roughened and worn, with the result that it will fail to fit fluid tight over the mouth of the bottle, 20 and leakage will ensue.

In accordance with the present invention, this objectionable action is obviated by so mounting the sealing member in its holder or cap, that while said member will be retained 25 therein, the holder will be capable of a circumferential movement relatively thereto; whereby the holder may be turned or screwed down to force the sealing member against the mouth of the receptacle, without at the same 30 time turning and grinding the sealing member against said mouth.

In the specification to follow, the invention will be described in detail, and the novel features thereof will be pointed out in the appended claims.

In the accompanying drawings:

Figure 1 is a longitudinal section through the improved closure, showing the same applied to close the mouth of a bottle, a portion 40 of which later is also shown in longitudinal section;

Fig. 2 is a horizontal section through the upper portion of the closure on the line 2—2 of Figure 1; and

Fig. 3 is a perspective view of the parts of the closure separated from each other.

Referring to the drawings:

The improved closure in the particular embodiment shown by way of example to illustrate the invention, comprises a sealing mem-

ber 1 adapted to close over and seal the mouth of the neck 3 of a bottle or receptacle 4; a holder 5 for said sealing member adapted to surround the same and fit over the bottle neck, and adapted by a turning movement to engage with said neck and thereby force the sealing member against the mouth of the same; and a retaining device 6 to engage the sealing member and retain the same in the holder 5.

The holder 5 in the present instance, is in the form of a tubular metal cap, whose closed end is enlarged radially as at 5^a to form an internal chamber to receive the sealing member, and whose neck portion 5^b is reduced in diameter and is provided with means for so engaging the neck of the bottle, that when the holder is turned, it will force the sealing member against the bottle mouth. This engaging means in the present instance is in the form of screw threads 5^c on the neck portion of the holder adapted to engage similar screw threads 3^a on the bottle neck.

The sealing member 1 in the present instance, is in the form of a cup or holder 1^a containing a filler 1^b of suitable resilient sealing material, such for instance as cork, the said cup being formed in its outer side with a peripheral groove for depression 1^c for the engagement of the retaining device 6.

This retaining device may be of any suitable form which will confine the sealing member within the holder while permitting of a circumferential movement of the latter relative to the former, and for this purpose I 75 preferably construct the sealing member in the form of a split spring ring 6^a adapted to be expanded to clamp around the cup or holder of the sealing member, after the latter is seated in the enlarged end of the holder 5. The sealing member is of such size that it can be inserted freely through the neck portion of the holder 5, and such that when the split ring is expanded to clamp around the sealing members, the external diameter of the expanded ring will be greater than the internal diameter of the neck 5, thereby preventing the escape of the sealing member from the holder, and will be less than the internal diameter of the enlarged portion of 100

the holder, thereby permitting the holder to turn circumferentially relative to the confined sealing member.

In assembling the parts of the closure, the sealing member is first inserted through the neck portion of the holder 5 and into the enlarged end 5^a thereof. The spring ring 6^a is then inserted in the neck portion of the holder and is expanded and forced over the sealing member so as to seat in the peripheral groove 1^c in the cup 1^a, and thus be clamped firmly around the same. Due to the fact that, as above explained, the external diameter of the spring ring when thus expanded is greater than the internal diameter of the contracted neck portion 5^b of the holder, and is less than the internal diameter of the enlarged portion 5^a of the holder, the sealing member will be retained loosely within the holder, and at the same time will be prevented from accidental escape therefrom. As a result, when the holder is screwed down on the bottle, its closed end will engage the sealing member and force the same against the mouth of the bottle neck, in which action, the holder will turn around relative to the sealing member and without turning the latter, the result being that the sealing member will be forced tightly to its seat without grinding or wear thereon.

Due to the manner of confining the sealing member within its holder as above described, the sealing member may be removed from the holder at will when it is desired to renew or replace said member, which removal may be readily effected by introducing a suitable tool or instrument into the holder and engaging it with the retaining spring, so as to expand the spring and disengage it from the sealing member, whereupon both the sealing member and spring may be removed separately from the holder.

It will be obvious that while the invention is shown as applied in connection with a receptacle in the form of a bottle, it will be applicable as well to other forms of receptacles, such as jars, cartons, and similar receptacles; and while the invention is illustrated as embodied in a certain detailed form and arrangement of parts, it will be understood that these details may be variously modified and changed by the skilled mechanic without departing from the spirit of the invention; and it will be further understood that the invention is not limited to any particular form or construction of the parts, except in so far as such limitations are specified in the claims.

Having thus described my invention, what I claim is:—

66. 1. A closure for receptacles comprising a member to close over and seal the open mouth of the receptacle, a holder for the sealing member surrounding the same and adapted by a turning movement to be engaged with the receptacle and force the sealing member

against the mouth thereof, and a retaining device for confining the sealing member in the holder while permitting of a circumferential movement of the holder relative thereto, said retaining device being in the form of a spring engaged with the sealing member and detachably interlocked with the holder. 70

2. A closure for receptacles as defined in claim 1, characterized by the fact that the retaining device is in the form of a split ring, 75 engaging the sealing member, and disconnected from the holder.

3. A closure for receptacles defined in claim 1, characterized by the fact that the retaining device is in the form of a split ring 80 clamped to the sealing member and movable circumferentially relative to the holder.

4. A closure for receptacles comprising a member to close over and seal the open mouth of the receptacle, a holder for the sealing member in the form of a cap enlarged radially at its closed end to receive the sealing member, and having a contracted open necked portion, said holder being adapted by a turning movement to be engaged with the receptacle and force the sealing member against the mouth thereof, and a split ring insertable through the contracted neck of the holder and expandable to clamp around the sealing member, the diameter of said ring when expanded, being greater than the internal diameter of said neck, and less than the internal diameter of said enlarged portion of the cap; whereby the sealing member will be retained in the enlarged portion of the cap, while permitting of a circumferential movement of the cap relative thereto. 95

In testimony whereof, this specification has been duly signed by:
